UNITED STATES PATENT OFFICE.

ABRAHAM B. LANDIS, OF ENFIELD, PENNSYLVANIA.

CUTTER-HEAD.

1,127,457.

Specification of Letters Patent.

Patented Feb. 9, 1915.

Application filed March 6, 1912. Serial No. 681,873.

To all whom it may concern:

Be it known that I, ABRAHAM B. LANDIS, a citizen of the United States, residing at Enfield, Montgomery county, and State of Pennsylvania, have invented and discovered certain new and useful Improvements in Cutter-Heads, of which the following is a specification.

My said invention consists in certain improvements in the construction and arrangement of parts of cutter-heads, whereby a conveniently and easily operated head for the purpose is provided and one wherein the die is rigidly supported, all as will hereinafter be more fully described and claimed.

Referring to the accompanying drawings, which are made a part hereof, and on which similar reference characters indicate similar parts, Figure 1 is a view chiefly in front elevation, showing a cutter-head embodying my said invention, Fig. 2 a view partly in cross section on the dotted line 2—2 in Fig. 1, Fig. 3 a detail section on the dotted line 3—3 in Fig. 2, Figs. 4, 5, 6 and 7, detail views illustrating separate parts more clearly, and Fig. 8 a detail section on the dotted line 8—8 in Fig. 1.

In said drawings the portions marked A represent the body of the head, B an annular frame surrounding said body and C the cutter-holder.

The body A is a casting of suitable form and size adapted to be mounted on the spindle or turret of the machine and formed with a central aperture surrounded by bearings for the cutter-holder trunnions arranged equi-distant from the axis. The annular frame B surrounds said body A and is secured thereto by screws b¹. It is formed with radial sockets b in which are hollow cylinders 10, each of which has a pinion 11 formed on its outer end. There are four of said sockets arranged equi-distant from each other around the interior of the forward end of said frame, as best shown in Fig. 1, and one of the cutter-holders is radially supported by the parts associated with each. The showing and description of one set of such parts will therefore be understood to apply to all. Each cylinder 10 is perforated longitudinally, the perforation being somewhat larger in diameter at its inner end than at its outer end, both sections being interiorly screw-threaded. A plug 12 is screwed into its inner end and is formed with a seat for the spherical head of a brace

bar 13, interposed between said plug and an appropriate seat in the outer corner of the cutter-holder in which a similarly formed opposite end of said brace bar rests. 60 A screw-threaded shank 14 is mounted in the outer end of cylinder 10 and has a head 15 of the form best shown in Fig. 5. One edge of said head is formed with a notch n with which a pin p engages. Said pin is 65 mounted in a perforation in the side of socket b and projects to the interior to make said engagement. The top of head 15 has a double inclined face, the portion 16 being of a sharp angle and the portion 17 of but 70 a slight angle. A ring 20 is mounted on frame B having a flange which extends through a slot in the adjacent side of said frame, said flange being formed with teeth on its inner edge which extend into mesh 75 with the teeth of pinions 11 on the several cylinders 10. Said ring 20 is provided with a series of sockets s for the insertion of a handle (not shown) for rotating the same and with an annular groove in which a ring 21 is mounted. Sliding bars 22 with double faced cams corresponding to the angles 16 and 17 of head 15, are attached to said ring 21 and adapted to slide longitudinally with ring 21. The end of said bar has a sharp angle 23 corresponding to the sharp angle 16 of said head. A spring-mounted detent 40 is mounted in a radial socket in ring 20, the inner end of which is adapted to engage with a conical depression 41 in the frame B. Said detent serves to hold ring 20 with the parts in closed position, but when force is applied to said ring, said detent will yield by reason of the tapered sides of the depression with 80 which it engages, permitting the operation without undue resistance. As shown in Fig. 2, the inner end of said detent bears upon the outer face of the depression with which it engages and the spring thus normally tends to hold the parts toward the front of the head and into operative engagement and also to keep the parts in close contact. Ring 20 is formed with an annular groove b² with which a shifting 100 fork (not shown) engages for operating the same. Ring B¹ surrounds the outer end of frame B covering the outer ends of sockets b and the grooves in which bars 22 slide, being secured to frame B by screws 50 inserted through perforations in said ring into screw-threaded perforations in said 110

frame at appropriately spaced intervals around the head.

The cutter-holders C are formed with trunnions C¹ mounted in the journals in the body A and are supported at their outer ends by the braces 13, one end of which rests in the plug 12 and the other in a suitable bearing in the inner end of each of said cutter-holders, as before described. A spring S (see Fig. 8) is mounted in a suitable recess in the body between the cutter-holder bearings and engages with each cutter-holder for normally holding it outward, as shown in several of my former patents, for example, No. 1,017,882, dated February 20, 1912.

The cutters C² are mounted in recesses in the face of the cutter-holders C and are clamped at their outer edges by means of inter-engaging tapered faces by a clamping plate 25 having a cam face 26 adapted to bear against the inner tapered face of the cutter. Said clamping plate is operated by clamping screw 27 having a cone-shaped inner end which engages with the cone-shaped perforation 28 in said plates.

The operation is as follows:—The parts being assembled as shown in Figs. 1 and 2, the operation of cutting proceeds until the finishing cut on the work is made, when the movement longitudinally between ring 20 and the annular frame B, takes place, which slides bars 22 over heads 15 until the sharp angles strike each other when the springs are permitted to turn the cutter-holders on their trunnions and open the die. When it is desired to close the die, ring 20 is returned to position which forces cylinders 10 inwardly and the cutter-holders into closed position. When it is desired to adjust the die for work of different sizes, it is done by turning ring 20 through the medium of a handle inserted in a socket s therein, which operates through the gear connections with the cylinders 10 to rotate said cylinders and adjust them radially on the threaded shanks 14, as will be readily understood. By turning the plugs 12 independently of the cylinders 10 each of said bearings may be adjusted independent of the others, so as to secure a uniform adjustment of the several parts.

Having thus fully described my said in-

vention what I claim as new and desire to secure by Letters Patent, is:

1. A cutter-head comprising a body, cutter-holders pivoted around the axis of said body, braces for supporting said cutter-holders in relation to the rim of said body, and sliding cam faces for operating the braces radially for effecting the adjustment, substantially as set forth.

2. A cutter-head comprising a body, cutter-holders mounted on trunnions pivoted in bearings around the axis of said body, radially adjustable supports in the rim of said body, braces interposed between the outer corners of said cutter-holders and said supports, and cams for operating said braces and supports radially to open and close the die, substantially as set forth.

3. A cutter-head comprising a body, cutter-holders pivoted around the axis of said body, a sliding ring on said body, rests carried on said body, braces interposed between said rests and said cutter-holders, and means for moving said braces radially to open and close the die, substantially as set forth.

4. A cutter-head comprising a body, cutter-holders pivoted around the axis of said body, a sliding ring mounted on said body, radially adjustable rests on said body, braces interposed between said rests and said cutter-holders, and cams mounted to slide longitudinally of said body for adjusting said rests radially, to open and close the die, substantially as set forth.

5. A cutter-head comprising a body, cutter-holders pivoted around the axis of said body, means for normally turning said cutter-holders on their pivots to open the die, a sliding ring surrounding said body, radially adjustable rests carried on said body, braces interposed between said rests and said cutter-holders, sliding cams for operating said rests radially, and means for sliding said cams, substantially as set forth.

In witness whereof, I have hereunto set my hand and seal at Washington, D. C., this 16th day of February, A. D. nineteen hundred and twelve.

ABRAHAM B. LANDIS. [L. S.]
